(57) **CLAIM**

The ornamental design for a shaft for golf club, as shown and described.

DESCRIPTION

FIG. 1 is a front view of a shaft for golf club;

FIG. 2 is a left side view thereof, the opposite side being a mirror image of the side shown herein;

FIG. 3 is an enlarged front view thereof; and,

FIG. 4 is an enlarged left side view thereof.

The portion shown by broken lines is for illustrative purposes only and forms no part of the claimed design.
